COMBINED ASH TRAY AND STAND

Filed Dec. 16, 1929

*Inventor:
Louis Hoffberg*

*John B. Carpenter
Atty.*

UNITED STATES PATENT OFFICE

LOUIS HOFFBERG, OF CHICAGO, ILLINOIS, ASSIGNOR TO VIDRIO PRODUCTS CORPORATION, OF CHICAGO, ILLINOIS, A CORPORATION OF ILLINOIS

DESIGN FOR A COMBINED ASH TRAY AND STAND

Application filed December 16, 1929. Serial No. 33,809. Term of patent 14 years.

To all whom it may concern:

Be it known that I, LOUIS HOFFBERG, a citizen of the United States, residing at Chicago, county of Cook, and State of Illinois, have invented a new, original, and ornamental Design for a Combined Ash Tray and Stand, of which the following is a specification, reference being had to the accompanying drawing, forming a part thereof.

On the drawing:

The single figure is a perspective view of a combined ash tray and stand showing my new design.

I claim:

The ornamental design for a combined ash tray and stand as shown.

LOUIS HOFFBERG.
